(57) **CLAIM**

The ornamental design for an automotive spoiler, as shown and described.

DESCRIPTION

FIG. 1 is a perspective view of the ornamental design for an automotive spoiler.

FIG. 2 is a top down view of the ornamental design for an automotive spoiler.

FIG. 3 is a bottom view of the ornamental design for an automotive spoiler.

FIG. 4 is a front view of the ornamental design for an automotive spoiler.

FIG. 5 is a back view of the ornamental design for an automotive spoiler.

FIG. 6 is a left side view of the ornamental design for an automotive spoiler; and,

FIG. 7 is a right side view of the ornamental design for an automotive spoiler.

The broken lines showing portions of the automotive spoiler form no part of the claimed design.
